UNITED STATES PATENT OFFICE.

GEORGE H. TABER, OF BINGHAMTON, NEW YORK, ASSIGNOR TO EMCO MANUFACTURING COMPANY, INC., OF BINGHAMTON, NEW YORK, A CORPORATION OF NEW YORK.

DEVICE FOR REFINISHING AXLES, CRANK-SHAFTS, &c.

1,345,809.

Specification of Letters Patent.

Patented July 6, 1920.

Application filed December 26, 1919. Serial No. 347,632.

To all whom it may concern:

Be it known that I, GEORGE H. TABER, a citizen of the United States of America, and a resident of Binghamton, in the county 5 of Broome and State of New York, have invented certain new and useful Improvements in Devices for Refinishing Axles, Crank-Shafts, &c., of which the following is a specification.

10 This invention relates to an improvement in a device for re-finishing the surfaces of shafting, axles, crank shaft bearings, etc., and the object of the invention is to provide a device of this kind which 15 will be simple in construction, effective, and convenient in use.

The invention consists in the construction and arrangement of parts hereinafter more particularly described and then definitely 20 claimed.

In the drawings accompanying and forming part hereof:

Figure 1 is a perspective view of my invention.

25 Fig. 2 is a vertical transverse section of the same.

Fig. 3 is a perspective view of the sliding carriage detached.

Referring now to the details of the drawings by numerals: 1 and 2 designate two oppositely disposed frame members preferably of the shape illustrated in Fig. 1. The lower frame member 1 is provided with two upwardly projecting lugs 3 and 4 adapted 30 to receive and support two threaded rods 6 and 8, these rods being firmly secured in the lugs 3 and 4, as shown. The bottom frame 35 1, between the lugs 3 and 4, is provided with a way or guide 14 upon which is slidably supported a longitudinally movable carriage 16, a screw 18 being employed to hold this carriage upon its way or guide 14, the carriage 16 having a longitudinal slot 20 permitting movement on the afore- 40 said way or guide 14. Any desirable form of cutting instrument or file 22 is secured to this carriage 16 so as to move therewith. An adjusting screw or bolt 24 is provided which is threaded through the lug 3 and 45 bears upon the end of the carriage 16 so that, when said bolt 24 is screwed into the lug 3, it will press against the carriage 16 and move it along its way 14 until it reaches the end of its movement.

50 55 The aforesaid upper frame member 2 is

provided with two bosses 26 and 28 which slip over the aforesaid threaded rods 6 and 8 and are capable of moving up and down on said rods, wing nuts 30 and 32 being provided on said threaded rods, over said 60 bosses 26 and 28, for the purpose of forcing the upper frame member 2 toward the lower frame member 1, in a manner readily understood from the drawings.

Secured to the under side of the upper 65 frame member is a block 34 of inverted V-shape which is arranged to hold the shaft properly located during the process of refinishing the untrue surface. This inverted V block 34 preferably is provided with two 70 recesses 36 and 38 which are for the purpose of holding thick pieces of felt 39, the felts being flat and of sufficient thickness to fit in the recesses 36 and 38 whereby they are more easily held in position. The duty 75 of the felt is to prevent the filings from embedding in the V block, thereby resulting in tearing or cutting the shaft while in operation.

Each of the frames 1 and 2 is provided 80 with an outwardly extending lug, these lugs being designated by the numbers 40 and 42. The purpose of these lugs is to receive a piece of pipe to act as a handle when necessary.

85 In the operation of the device, the adjusting screw or bolt 24 may be operated, as occasion requires, to bring a new part of the file 22 in place, thus eliminating the necessity of many removals of the file during the process of truing up the surface of the shaft being operated upon, it being understood that the feed screw causes the clean part of the file to engage with the shaft surface being filed. If the device 90 should be turned in the wrong direction, the carriage 16 will automatically slide along its way or guide 14 and thus give warning to the operator that the device is being turned in the wrong direction.

100 What I claim as my invention is:

1. In a device of the character described, two frame members adjustable toward each other, one of said members having a clamping member and the other a sliding carriage 105 provided with a cutting tool, substantially as described.

2. In a device of the character described, two frame members adjustable toward each other, one of said members having a clamp-

ing member and the other a sliding carriage provided with a cutting tool, and a screw or bolt for moving said carriage and its tool to present a new part of the tool to the work, substantially as described.

3. In a device of the character described, two frame members, one having screw rods projecting therefrom and the other having parts sliding over said screw rods, nuts on 10 said screw rods for moving one of said frame members toward the other to clamp the work, a carriage on one of said members provided with a tool, and a screw or bolt for adjusting said carriage and its tool, substantially as described.

4. In a device of the character described, two frame members adjustable toward each other, one of said members having a V-shaped clamping member provided with oppositely disposed recesses, and felt brushes located in said recesses projecting toward each other, substantially as described.

5. In a device of the character described, two frame members adjustable toward each other, one of said members having a V-shaped clamping member and the other an adjustable sliding carriage provided with a cutting tool, and felt brushes carried by said V-shaped clamping member.

30 6. In a device of the character described, two frame members adjustable toward each other, one of said members having a clamping member and the other a sliding carriage provided with a cutting tool, and a screw or bolt for moving said carriage and its tool to present a new part of the tool to the work, said carriage being free to slide away from said screw or bolt if the device is turned in the wrong direction, substantially 35 as described.

40 7. In a device of the character described, two frame members adjustable toward each other, one of said frame members having a V-shaped clamping member and the other a 45 guideway, a carriage slideable on said guide-

way and provided with a tool, and a screw or bolt for moving said carriage on its guideway to present a new part of the tool to the work, substantially as described.

8. In a device of the character described, 50 two frame members adjustable toward each other, one of said frame members having a V-shaped clamping member and the other a guideway, a carriage slideable on said guideway and provided with a tool, and a screw 55 or bolt for moving said carriage on its guideway to present a new part of the tool to the work, said carriage being adapted to move away from said screw if the device is turned in the wrong direction, substantially as described.

9. In a device of the character described, two frame members adjustable toward each other, one of said members having a clamping member and the other a sliding carriage 65 provided with a cutting tool, each of said frame members having a lug to receive a pipe, substantially as described.

10. In a device of the character described, two frame members, one having two bosses 70 projecting therefrom, and provided with a guideway, screw rods projecting from said bosses, the other frame member having a V-shaped clamping member located over said guideway, a carriage slideable on said 75 guideway under said V-shaped clamping member, a screw passing through the end of the frame and co-acting with said carriage to move the carriage and its tool on said guideway to present a new part of the tool 80 to the work, and nuts on said screw rods for moving the upper frame member and its V-shaped clamping member toward the carriage and its tool, substantially as described.

In testimony whereof I affix my signature 85 in presence of two witnesses.

GEORGE H. TABER.
